(57) **CLAIM**

The ornamental design for a front piece of a baby carrier, as shown and described.

DESCRIPTION

FIG. 1 is a front perspective view showing our new design for a front piece of a baby carrier,

FIG. 2 is a rear perspective view thereof,

FIG. 3 is a front view thereof,

FIG. 4 is a rear view thereof;

FIG. 5 is a left side view thereof, the opposite side being a mirror image,

FIG. 6 is a top view thereof,

FIG. 7 is a bottom view thereof,

FIG. 8 is a supplemental figure of FIG. 1, without environmental broken lines,

FIG. 9 is a supplemental figure of FIG. 2, without environmental broken lines,

FIG. 10 is a supplemental figure of FIG. 3, without environmental broken lines,

FIG. 11 is a supplemental figure of FIG. 4, without environmental broken lines,

FIG. 12 is a supplemental figure of FIG. 5, without environmental broken lines,

FIG. 13 is a supplemental figure of FIG. 6, without environmental broken lines; and,

(Continued)

FIG. 14 is a supplemental figure of FIG. 7, without environmental broken lines.

The broken lines illustrate portions of the front piece of a baby carrier that form no part of the claimed design.
